TELEPHONE STAND HOLDER

Paul E. Bauer, Westbury, N. Y.

Application August 6, 1935, Serial No. 35,004

9. Claims. (Cl. 40—10.5)

This invention relates to stand holders and has for an object to provide an improved construction which may be used with telephones or other objects for supporting the same and also providing additional attachments.

Another object of the invention is to provide a holder for stands wherein means are provided for holding a pad and pencil in a normal out-of-the-way position but ready for instant use.

10 An additional object is to provide a support or holder for stands wherein there is provided an annular ring which may be rotated and which is formed with means for supporting a strip of paper, tape, or the like having desired information thereon which is readily accessible at all times.

In the accompanying drawing—

Figure 1 is a side view of a holder disclosing an embodiment of the invention, the same being shown in connection with a telephone stand;

Fig. 2 is a top plan view of the holder shown in Fig. 1; and

Fig. 3 is a sectional view through Fig. 1 approximately on the line 3—3.

25 Referring to the accompanying drawing by numerals, 1 indicates the body of the holder, said body being formed with a casing 2 of metal, wood, bakelite, or other material, and provided with a suitable filling section 3 of cardboard, paper, fiber, wood, or other material. The filling section 3 is so arranged that there are provided cavities 4 and 5, cavity 5 being adapted to receive and hold a pencil 6, while cavity 4 is adapted to receive a drawer 7 which drawer preferably has 30 no sides but has a bottom 8 and ends 9 and 10 together with a handle 11. Different articles may be carried in this drawer, as, for instance, a pad 12. It will thus be seen that the pad 12 and pencil 6 are readily accessible but normally out of 35 the way.

The body 1 is shown as round and this is the desirable form but it could be made of some other shape if desired.

40 In the accompanying drawing the holder has been shown as means for holding and supporting a telephone stand. In order to do this properly there are provided resilient holding catches or prongs 13 which may be welded or otherwise rigidly secured to the casing 2. These prongs are 45 formed as shown in the drawing whereby the base 14 of the telephone may be merely forced downwardly until it engages the upper surface of the casing 2 and these resilient prongs will snap 50 into position as shown in the drawing and nor-

mally hold the parts together so that if the telephone is lifted and transported the holder also will be transported though they may be pulled apart.

The casing 2 while it may be made of different materials is preferably made of metal and at the periphery is provided with a pair of spaced upstanding rings 15 and 16 whereby there is an annular groove 17 in which a depending annular flange 18 slidably fits. This flange is preferably 5 integral with a runway or band-receiving collar 19. These parts may be made from bakelite, rubber, metal, or other material, but are preferably made from metal and preferably bent at an angle as shown in Figs. 1 and 3, though they 10 could stand upright or even be laid horizontal if preferred. In forming the runway 19, the respective edges are turned over at 20 and 21 to form grooves for the reception of a strip or ring of paper or other material 22. The strip or ring 15 of paper 22 may be tightly held in the runway 19 or loosely held therein. When the strip of paper 20 is loosely held it may be moved with the finger of the operator so that different points may come 25 opposite the operator as desired. However, usually the ring 22 is held by friction so as not to readily move but the runway 19 will readily slide in the groove 17 so that any point on the face of the ring 22 may be brought opposite the operator. This ring may contain any desired information, 30 as, for instance, the names and addresses of customers, friends, or the like; also telephone numbers may be arranged on this ring or strip of paper, as it is easily rotated by reason of the movement of the runway 19. Any of these 35 addresses or telephone numbers may readily be brought in front of the operator. It will be readily understood that the ring 22 may be removed at any time and a new one substituted so that other information may be applied thereto. In 40 many cases it may be desired to place advertising matter over the entire surface of the ring 22, or at certain places thereon, so that the user of the device may have part of the ring for his individual use while the remaining part will call to his 45 attention the goods of the various advertisers.

I claim:

1. A telephone stand holder, comprising a body, means carried by said body adapted to clamp the base of a telephone thereon, an upstanding pair of spaced concentric rings carried by said body adjacent the periphery thereof, and an article-carrying member having a ring-shaped extension loosely mounted in the space between 50 55

- said spaced rings whereby said article-carrying member may be rotated.
2. A telephone stand holder adapted to receive and support a telephone, comprising a circular body for receiving the base of a telephone, a plurality of resilient fingers carried by said body for resiliently and removably clamping said base on said body, and a rotatable article carrier supported by said body and extending substantially around the periphery thereof, said carrier having inturned facing flanges for producing facing grooves adapted to receive a band of paper or the like.
3. A device of the character described comprising a circular base, a circular track surrounding said base and carried by the base at the periphery thereof, and a circular indicia-band holding runway rotatably mounted in said track.
4. A telephone stand holder comprising a body, an upstanding pair of concentric spaced rings carried by said body surrounding the periphery thereof, and an article-carrying ring-shaped member loosely mounted in the space between said spaced rings whereby said article carrying member may be rotated horizontally between said concentric upstanding rings.
5. A telephone stand holder comprising a body having a circular base, means carried by the body acting to clamp the base of a telephone thereon, a circular track mounted on the upper surface of the base at its periphery and a circular indicia-carrying band mounted in said track.
6. A telephone stand holder comprising a body having a circular base, means carried by the body acting to clamp the base of a telephone thereon, a circular track connected to and surrounding said base at its periphery and adapted to carry a circular indicia-band holding runway 5 rotatably mounted in said track.
7. A stand holder comprising a body having a circular base, means carried by the body for clamping a stand thereon, a circular track permanently secured to and surrounding said base at 10 its periphery, an information-bearing ring, and means for rotatably mounting said ring on said track.
8. A stand holder comprising a body having a circular base, a circular track carried by said 15 base, and a rotatable circular ring surrounding said base at the periphery thereof with a portion slidingly fitting in said track, said rotatable ring having turned-over edges for presenting facing grooves adapted to receive an information-carrying ring.
9. A telephone stand holder comprising a body, means carried by said body adapted to clamp the base of a telephone thereon, an upstanding pair of concentric spaced rings carried by said body 25 surrounding the periphery thereof, and an article-carrying ring-shaped member loosely mounted in the space between said spaced rings whereby said article-carrying member may be rotated horizontally between said concentric up-standing rings.

PAUL E. BAUER.
